Specification for Design.

Patented Dec. 12, 1916.

Application filed October 9, 1916. Serial No. 124,736. Term of patent 3½ years.

To all whom it may concern:

Be it known that I, DONALD CAMPBELL, a citizen of the United States, residing at Chicago, in the county of Cook and State of Illinois, have invented a new, original, and ornamental Design for Harps, of which the following is a specification, reference being had to the accompanying drawings, forming part thereof.

Figure 1 is a perspective view of a harp illustrating my new design; Fig. 2 is an end elevation of the same.

I claim:

The ornamental design for a harp, as shown.

DONALD CAMPBELL.
